UNITED STATES PATENT OFFICE

GUSTAV JACOBSON AND GUNNAR F. ERICSON, OF NEW YORK, N. Y., ASSIGNEES TO
SUPERIOR FLOOR SURFACING MACHINE CORPORATION, OF NEW YORK, N. Y., A COR-
PORATION OF NEW YORK

FLOOR SURFACING MACHINE

Application filed April 11, 1927. Serial No. 182,597.

This invention relates to floor surfacing machines and aims to improve the construction and more particularly the operation of such machines.

5 The invention relates particularly to the type of floor surfacing machine which consists of a carriage which is pushed about by the operator, and has at its front end a rotary grinding drum. In the machines of this char-
acter now in use, it has been found that irregularities of the floor surface set up small but sustained vibrations in the grinding drum, which cause an objectionable ripple-like surface in the floor.

15 A particular object of the present invention is to avoid such vibration of the grinding drum. This we accomplish by mounting the drum on a lever or a pair of levers of the second or third class. The levers are ful-
crumed to the carriage at their inner ends, and carry the drum at their outer ends. Means for varying the pressure on the drum and for raising it when required engage the levers at intermediate points between their 25 fulcrums and the drum. This arrangement possesses several advantages. In the first place, the lever arm through which acts the weight of the drum, tending to hold the drum to the floor, is the entire length of the lever,

30 and may therefore be made several times as great as the radius of the drum without using an unduly long lever or carriage. This gives the weight of the drum an effect on the position of the lever materially greater than that 35 of the forces set up by changes in the friction between the drum and the floor, which act through an arm equal in length to the radius of the drum. A second advantage is that in such a lever of the second or third class, there 40 are not, as in the case of a lever of the first class, balancing forces which tend to sustain any vibrations which may occur in the drum. A third advantage is that the use of a lever fulcrumed at its inner end facilitates placing 45 the shaft, from which power is obtained to rotate the drum, close to the fulcrum point of the lever. A feature of the invention consists in driving the drum through a chain whose driving sprocket is mounted on a shaft 50 close behind the fulcrum of the lever, so that

movements of the lever about its fulcrum cause substantially no change in tension of the chain. This prevents up-and-down movements of the drum, caused by irregularities in the floor, from causing irregularity in the 55 driving force rotating the drum, and thus tends to prevent the forming of a ripple-like surface.

A further object of the invention is to provide improved control means for regulating 60 the pressure on the drum, and for raising the drum when desired. This and other features of the invention may best be understood from a detailed description of a practical floor surfacing machine embodying the invention, 65 which is shown in the accompanying drawings, in which:

Fig. 1 is a side view of the machine;

Fig. 2 is a longitudinal section of the ma-
chine taken on the line 2—2 of Fig. 3; 70

Fig. 3 is a horizontal section of the ma-
chine taken on the line 3—3 of Fig. 2;

Fig. 4 is a partial transverse section of the machine taken on the line 4—4 of Fig. 2, 75 indicating the drum and omitting other parts beyond the section plane; and

Fig. 5 is a fragmentary transverse section on the line 5—5 of Fig. 2, showing one of the drum bearings.

The machine illustrated includes a carriage 80 10 having a platform 11 and depending side flanges 12, 12' which are secured to the platform by means of stiffening angles 13. The carriage has between its side flanges, near its front end, a pair of wheels 14, 14' freely jour-
nalled on a bent shaft 15 extending between the side flanges. The rear end of the carriage is supported on a caster 16 mounted on a rearward projection 17 of a bracket 18, 85 which extends across the rear end of the carriage and provides also a rearwardly and up-
wardly inclined projection 19, to which is at-
tached a handle 20, by means of which the carriage is pushed about the floor by the operator.

90 A grinding drum 30 is mounted at the front end of the carriage. It consists of a hollow metal cylinder provided with an abrasive sur-
face. Its shaft 31 has its ends journaled in self-aligning ball bearings 32 in the disk- 100

shaped outer portions 33 of a pair of levers 34, 34'. These levers are fulcrumed to the carriage at their inner ends by means of pivots 35, 35' projecting outwardly from the side flanges 12, 12' of the carriage. The length of each lever is several times as great as the radius of the drum 30. Just inside the drum, the levers are connected by means of a tie rod 37 containing a universal joint 38. Bumpers 39 are carried in advance of the drum by arm 39' projecting from the disk-shaped portions 33 of the levers 34, 34', to prevent the drum from striking a wall.

Means are provided to permit an operator, who is pushing the carriage by means of the handle 20, to regulate the pressure between the grinding drum and the floor; also to raise the drum clear of the floor, so that the machine may be moved about easily when not in operation. Such means include a forked lever 40, which is fulcrumed to the side flanges 12, 12' by means of pivot bolts 41, 41' which pass through the two forwardly projecting arms 42, 42' of the forked lever. The arms 42, 42' carry at their outer ends blocks 43, 43' (which may be formed integral with the arms as shown) containing vertical holes. Tension rods 44, 44' fit loosely in the holes in the blocks 43, 43', and have at their upper ends, enlarged heads or nuts 45 resting on the upper surfaces of the blocks 43, 43'. The lower ends of the tension rods 44, 44' are secured in the tie rod 37 inside the side flanges 12, 12' and at opposite sides of the universal joint 38. Compression springs 46, 46' surround the tension rods 44, 44', so that they may react between the blocks 43, 43' and the tie rod 37 or nuts 48 set on the tension rods just above the tie rod.

It is apparent that if the lever 40 be tilted so as to cause the blocks 43, 43' at its outer end to move downward, each of the springs 46, 46' is compressed so as to urge each end of the grinding drum 30 against the floor more and more strongly. In this movement, each of the blocks slips down along the tension rod which passes through it. When the outer end of the lever is raised to bring the blocks into contact with the heads 45 of the tension rods, the downward pressure of the springs on the drum is at a minimum. By adjustment in the position of the heads 45 or the nuts 48, this minimum may be made whatever is required; or, if desired, the adjustment may be such that the springs are fully expanded when the blocks 43, 43' are in contact with the heads 45, so that the drum is held down by its own weight only. When the outer ends of the lever 40 are raised beyond the point at which the heads 45 of the tension rods come into contact with the blocks, the blocks raise the tension rods and lift the grinding drum clear of the floor.

Such movements of the lever 40 are obtained by manipulation of a handle 50, piv-

oted to the handle 20 near its upper end. The handle 50 is connected with the lever 40 by force-increasing mechanism to facilitate compressing the springs 46, 46', or raising the drum 30 by means of the handle. Such mechanism includes a link 51, whose upper end is pivoted to the handle 50 at 52, and whose lower end is pivoted at 53 to the rear end of an arm 54, which is fixed to, and extends rearwardly from, a gear segment 55 journalled at 56 to the depending flange 57 of an angle plate 58 secured to the bottom of the platform 11. The gear segment 55 meshes with a corresponding gear segment 59, journalled on the flange 57 at 60. To this gear segment 59, the rear end of the forked lever 40 is connected by means of a pivot bolt 61 projecting from the segment between its axis and its teeth and passing through a slot 62 in the lever.

When the handle 50 is allowed to stay in its normal position, shown in Fig. 1, the grinding drum rests on the floor, either under its own weight only or with the addition of a minimum spring pressure. When the handle 50 is pushed downward from its normal position, the rear end of the forked lever 40 is raised and its forward end is depressed to compress the springs 46, 46', and thus increase the downward pressure on the drum. The exact amount of the pressure obtained during the operation of the machine may, therefore, be regulated by pushing down to a greater or less extent on the handle 50.

When the handle 50 is raised from its normal position, the outer end of the lever 40 is raised, drawing up the tension rods 44, 44', and lifting the grinding drum off the floor into an inoperative position. A notch 63 in an arc 64, secured to the handle 20, may be provided for holding the drum off the floor by cooperation with a latch 65 on the handle 50.

The grinding drum 30 is rotated by means of an electric motor 70, mounted on the platform 11 of the carriage. Through a chain 71, this motor drives a shaft 72 extending across the carriage and journalled in its side flanges 12, 12'. From a sprocket 73 fixed on the shaft 72, the power is transferred to a sprocket 74 fixed on the drum shaft 31 by means of a chain 75. It should be particularly noted that the driving shaft 72 is located close to the fulcrum 35, 35' at the rear ends of the lever 34, 34' and directly behind the rear ends of the levers, so that up-and-down movements of the drum 30, and corresponding movements of the levers 34, 34', have practically no effect upon the tension of the chain 75. This prevents up-and-down movements of the drum, which may be caused by irregularities in the floor surface, from making the rotation of the drum uneven.

The dust produced by the drum in grinding is directed by the drum into a dust pan 80 located just inside the drum. The outer

ends of this pan are secured to the levers 34, 34' by strips of sheet metal 81, which bend so easily that the pan does not interfere with independent up-and-down movement of the 5 two levers. The dust is drawn from the pan 80 by a suction blower 82 driven by the motor 70 and is deposited in a bag 83, indicated in dot-and-dash lines in Fig. 1. A pipe 84 connecting the bag with the blower has a 10 flexible portion 85 so as not to interfere with free movement of the levers 34, 34'.

What is claimed is:

1. In a floor surfacing machine having a carriage and a rotary grinding drum at the 15 front end of the carriage and movable vertically, drum-controlling mechanism comprising two intermeshing gear segments pivotally mounted on the carriage, one of which has an arm projecting rearwardly from its axis, 20 a control handle connected to said arm, and a lever fulcrumed on the carriage and having its rear end pivotally connected to the other gear segment between the axis and the teeth of the gear segment, the front end of said 25 lever being operatively connected to the drum.

2. In a floor surfacing machine having a carriage and a rotary grinding drum at the front end of the carriage, separately vertically movable mountings for the two ends of 30 said grinding drum, and drum-controlling mechanism comprising two intermeshing gear segments pivotally mounted on the carriage, one of which has an arm projecting 35 rearwardly from its axis, a control handle connected to said arm, a forked lever fulcrumed on the carriage and having its single rear end pivoted to the other gear segment between the axis and the teeth of the gear 40 segment, rods extending downward through openings in the forked front ends of said lever and connected to said drum mountings, nuts on said rods above the lever ends, and compression springs on said rods below the 45 lever ends.

In testimony whereof we have hereunto set our hands.

GUSTAV JACOBSON.
GUNNAR F. ERICSON.
